US0D1032555S

(12) **United States Design Patent** (10) **Patent No.:** **US D1,032,555 S**
(45) **Date of Patent:** **** Jun. 25, 2024**

(54) **PARENT UNIT**

(71) Applicant: **Shenzhen Mingchuangzhilian Technology Co., Ltd**, Shenzhen (CN)

(72) Inventor: **Dunming Shuai**, Shenzhen (CN)

(73) Assignee: **SHENZHEN MINGCHUANGZHILIAN TECHNOLOGY CO., LTD**, Shenzhen (CN)

(**) Term: **15 Years**

(21) Appl. No.: **29/851,665**

(22) Filed: **Aug. 31, 2022**

(51) LOC (14) Cl. **14-03**

(52) U.S. Cl.

USPC **D14/159**

CLAIM

The ornamental design for a parent unit, as shown and described.

DESCRIPTION

FIG. 1 is a perspective view of a parent unit showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the parent unit in a second state.

The broken lines in the drawings are for the purpose of illustrating portions of the parent unit that form no part of the claimed design.

1 Claim, 9 Drawing Sheets
